UNITED STATES PATENT OFFICE.

JOHN L. DONNER, OF OREGON CITY, OREGON, ASSIGNOR, BY DIRECT AND MESNE ASSIGNMENTS, TO JOHN BROSNAN, JR., OF WASHINGTON, DISTRICT OF COLUMBIA.

EXPLOSIVE POWDER.

1,214,765.

Specification of Letters Patent.

Patented Feb. 6, 1917.

No Drawing.

Application filed June 13, 1916. Serial No. 103,567.

To all whom it may concern:

Be it known that I, JOHN L. DONNER, citizen of the United States, residing at Oregon City, in the county of Clackamas and State of Oregon, have invented certain new and useful Improvements in Explosive Powders; and I do declare the following to be a full, clear, and exact description of the invention, such as will enable others skilled in the art to which it appertains to make and use the same.

This invention relates to explosive powders, but more particularly to high explosives and bursting powders, and the invention has for its object to provide powders of this class which are safe to manufacture, free from injurious effects upon operatives during the process of manufacture, and insensitive to a very safe degree.

A further object of the invention is to produce explosive powders of the high explosive or bursting type which can be uniformly and completely detonated by a detonating fuse and which possess the greatest degree of strength compatible with the conditions under which the powder is employed.

A further object of the invention is to provide an explosive powder of this type which will not be decomposed when same is hermetically sealed and subjected to a temperature of 65.5 C. for an appreciable length of time, and which will retain its properties under moisture when handled with ordinary care.

A further object of this invention is to provide an explosive powder of this type which has no injurious effect upon the ordinary metals and which will not deteriorate or undergo chemical change in storage.

A further object of this invention is to produce an explosive powder of this type which can be produced in large quantities in practically any locality, which is simple, cheap and easy to manufacture, and which is efficient in the greatest degree.

A further object of the invention is to provide an explosive powder of this type which can be loaded in projectiles compactly by compression with no unusual danger and requiring no exceptional skill or special methods.

With these objects in view the invention

consists in the novel mixture of chemical ingredients as will be hereinafter fully described.

In the production of high explosives and bursting powders according to this invention, I employ a moistening agent such as water, potassium chlorate, manganese dioxide, an organic matter soluble in water, and an oily substance such as crude oil.

By certain modifications in the relative proportions of the above ingredients, I am enabled to produce explosives and bursting powders having certain characteristics which adapt the powders to particular uses, but it is to be understood that this invention does not contemplate the use of a relatively large proportion of an oily substance or even a sufficient proportion thereof to render the composition wet or pasty, but on the other hand, I employ such a relatively small proportion of an oily substance that the presence thereof in the composition is negligible from a physical standpoint. The presence of an oily substance in the composition in a sufficient quantity to render the same damp or wet is a positive and decided detriment to the explosive. In the first place, as far as the explosive properties of the oily substance is concerned, it can be said to be a waste product in the composition as it adds nothing whatever to the explosive properties of the mixture. On the other hand it burns with a smoke, thereby seriously interfering with the smokeless properties of the explosive. Furthermore a sufficient quantity of an oily substance to render the composition damp or pasty very seriously interferes with the quick and proper drying of the explosive.

According to Example 1 which is particularly adapted as a rock of general mining powder, I employ the following formula:

Moisture 2%,

Potassium chlorate 46%,

Manganese dioxide 1%,

Organic matter soluble in water 49%,

An oily substance such as crude oil 2%.

These ingredients are brought together in the following manner:

The organic matter soluble in water, may be any organic matter having high carbon content such as sugar, glucose and like organic substances preferably of a sticky char-

acter. This organic matter is dissolved in 2% of water and is heated to the boiling point for several minutes. The manganese dioxid is then added to this plastic mass while the same is hot and the oily substance is then added while the mass is still hot. The potassium chlorate is then added to the mass while still hot, the result being a stiff plastic mass, which can be readily 10 granulated in the usual manner or otherwise formed. The mass is then dried at a temperature of 80° F.

Powder produced according to Example 1 is a slow powder, detonating, progressive 15 burning and safe. It is slow burning and in action similar to that of black powder except it is smokeless and gives off no poisonous gases. These characteristics particularly adapt the powder for use in blasting 20 ordinary rock and for general mining purposes.

According to Example 2, I mix the above named ingredients according to the following formula, which produces an efficient 25 powder for army work for the construction of trenches, destruction of bridges, etc., as follows:

Moisture 2%,
Potassium chlorate 47%,
30 Manganese dioxid 2%,
Soluble organic matter 48%,
An oily substance such as crude oil 1%.

The powder made according to this formula, the ingredients of which are brought 35 together in the order and in the manner in Example 1, produces a powder faster and more powerful than that under Example 1, which is due principally to a higher content of manganese dioxid and potassium 40 chlorate, and a lower content of the soluble organic matter. This powder according to Example 2 detonates with greater force than that under Example 1, is faster bursting and burns with more flame.

45 According to Example 3 which is particularly adapted as a stump powder, I employ the ingredients according to the following formula:

Moisture 1%,
50 Potassium chlorate 49%,
Organic matter soluble in water 47%,
Manganese dioxid 2%,
Oily substance such as crude oil 1%.

The ingredients are mixed in the order 55 and in the manner as under Example 1, and produces a detonating powder having the same general characteristics as that under Example 2, but has more lifting power, is faster than No. 2 and concentrates to a 60 greater extent than that under Examples 1 and 2. These characteristics particularly adapt the powder to the blowing up of stumps and for like and similar purposes.

According to Example 4 which is particularly adapted as a hard rock powder, I em-

ploy the same ingredients and bring them together the same as under the foregoing examples, but in the following proportions:

Moisture 2%,
Potassium chlorate 49%,
Organic matter soluble in water 45%,
60 Manganese dioxid 2%,
Oily substance such as crude oil 2%.

This produces a detonating powder faster than No. 3 due principally to a greater 65 proportion of potassium chlorate as compared with the water soluble organic matter, and a powder produced according to this example has a greater bursting force than those under the foregoing examples, 70 and is, therefore, particularly suitable for use on hard rock where it is desired to disintegrate the same.

According to Example 5 which produces a powder of high explosive force and is 75 particularly useful as a general engineering powder, the ingredients are brought together in the following proportions:

Moisture 2%,
Potassium chlorate 48%,
Organic matter soluble in water 46%,
80 Manganese dioxid 2%,
Oily substance such as crude oil 2%.

Powder produced according to this example does not have to be confined, and for 85 greatest efficiency should be of fine granulation.

According to the foregoing examples the manganese dioxid quickens the powder and increases its bursting force. The potassium 90 chlorate is what may be termed the base and main explosive content. The greater the content of chlorate and the less water soluble organic matter, the greater explosive force, but the more difficult to detonate. The 95 greater the content of carbon and the less content of potassium chlorate the more sensitive the powder. The presence of an oily substance such as crude oil acts as a cushion around the potassium chlorate and renders 100 the powder safe to handle, the greater the content of oil the less sensitive the powder.

Having thus fully disclosed the invention and the ingredients forming the explosive powder and having described several examples, it is of course, apparent that the ingredients forming this powder can be brought together in other and in varying proportions, and I do not consider myself limited to the exact proportions of the ingredients as specified in the foregoing examples, nor do I consider myself limited to the use of the exact ingredients as herein mentioned, but I do consider myself clearly entitled to any changes in the relative proportions of the ingredients and in the use of any similar ingredients having the same or like chemical characteristics. I, therefore, consider myself clearly entitled to any and all such changes and modifications as 115 120 125 130

fall within the limit and scope of the appended claims.

What I claim as new and desire to secure by Letters Patent of the United States is—

5 1. An explosive powder including a mixture of the following ingredients: water, potassium chlorate, manganese dioxid, sugar and crude oil, the last mentioned element being in such proportion in relation to the 10 composition, so as to allow for a quick and ready drying of the same.

2. An explosive mixture, consisting of a chlorate manganese dioxid, sugar and crude oil.

15 3. An explosive mixture consisting of particles of chlorate, manganese dioxid, sugar and crude oil, in which the crude oil forms

an envelop around the individual particles of chlorate.

4. The herein described process of producing an explosive compound which consists in mixing sugar with water and heating the same, then adding to the mass while hot manganese dioxid, then adding to the mass while hot crude oil, then adding to the mass while hot potassium chlorate and then drying the mixture.

In testimony whereof, I affix my signature, in presence of two witnesses.

JOHN L. DONNER.
